US00D402253S

United States Patent

[19]

Buechele

[11] Patent Number: Des. 402,253

[45] Date of Patent: **Dec. 8, 1998

[54] **RAIL FOR BACKING STRIP OF
WINDSHIELD WIPER SQUEEGEE**

3,117,336 1/1964 Reese .

[76] Inventor: **Franz Buechele**, 501 Hood Lake Rd.,
Lawrenceburg, Tenn. 38464

32 08 749 A1 3/1982 Germany .

2 243 991 11/1991 United Kingdom .

[**] Term: **14 Years**

Primary Examiner—Ralf Seifert

Attorney, Agent, or Firm—Bacon & Thomas

[21] Appl. No.: **58,185**

CLAIM

[22] Filed: **Aug. 9, 1996**

I claim the design for a rail for backing strip of windshield
wiper squeegee, as shown.

[51] LOC (6) Cl. **12-01**

DESCRIPTION

[52] U.S. Cl. **D12/220**

[58] Field of Search D12/219, 220;
15/250.07, 250.35, 250.36, 250.41, 250.42,
250.32, 250.33, 250.01, 250.14, 250.451,
250.452, 250.453, 250.454

FIG. 1 is a top plan view of a rail for backing strip of
windshield wiper squeegee showing my new design, the
bottom plan view being a mirror image thereof;
FIG. 2 is a right side elevation view thereof;
FIG. 3 is a left side elevation view thereof;
FIG. 4 is an end elevation thereof; and,
FIG. 5 is a perspective view thereof.
